(57) **CLAIM**

The ornamental design for a tire, as shown and described.

DESCRIPTION

FIG. 1 is a front view of a tire showing my new design; FIG. 2 is a rear view thereof;

FIG. 3 is a top plan view thereof, for which the bottom plan view is the same;

FIG. 4 is a right side view thereof;

FIG. 5 is a left side view thereof;

FIG. 6 is an enlarged view taken along line 6-6 in FIG. 1; and, FIG. 7 is a cross-sectional view taken along line 7-7 in FIG. 4 and line 7'-7' in FIG. 6.

In the drawings, the broken lines defining the sidewall, inner bead, and the peripheral boundary between the claimed tire tread and the unclaimed sidewall depict environmental subject matter that forms no part of the claimed design.
